HOLD-FAST DEVICE

George M. Doeber, Buffalo, N. Y.

Application April 16, 1935, Serial No. 16,693
Renewed January 21, 1936

3 Claims. (Cl. 24—139)

The invention relates to a hold fast device and more particularly to hold fast clothes pins.

The primary object of the invention is the provision of a device of this character, wherein the same when in use and engaged over a line bearing clothes or other articles the latter will be prevented from the accidental falling from the line, due to windy weather, and such device will have maximum life irrespective of the amount of usage thereof, it being practically indestructible and is readily and easily applied to a line and removed therefrom.

Another object of the invention is the provision of a device of this character, wherein the same supports a display sign adaptable to bear advertising matter, the device in its entirety being of novel construction.

A further object of the invention is the provision of a device of this character, which is extremely simple in construction, thoroughly reliable and efficient in its operation, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

30 In the accompanying drawing:

Figure 1 is an elevation of the device constructed in accordance with the invention.

Figure 2 is a rear view thereof.

Figure 3 is an edge elevation.

35 Figure 4 is a sectional view on the line 4—4 of Figure 1.

Figure 5 is a rear elevation of a modified form.

Figure 6 is a sectional view on the line 6—6 of Figure 5.

40 Similar reference characters indicate corresponding parts throughout the several views in the drawing.

Referring to the drawing in detail, particularly Figures 1 to 4, inclusive, the device which is in the nature of a hold fast clothes pin, comprises opposed substantially circular resilient jaws or clips 10 and 11, respectively, both being made from a single length of inherently resilient wire convoluted or coiled and the ends of this wire are brought together and linked by hook terminals 12, these terminals being disposed slightly offset from the jaw or clip 10 and inwardly toward the center thereof. The jaw or clip 11 is angularly bent at 13 so that the portion 55 will outwardly diverge from the portion adjacent thereto of the jaw or clip 10 thereby permitting

easy entrance of a clothes line between the jaws or clips 10 and 11 on pressing the clothes pin over such line for the fastening of articles hung thereon.

The jaw or clip 10 has formed therein transversely aligned bights 14 constituting seats for the line when engaged between the jaws or clips 10 and 11 and assuring hold fast action of the device.

A display plate 15 is carried by the device and 10 the same is formed with bendable tongues 16 which are folded over and about the wire at opposite sides of the hook terminals 12 thereof and this plate 15 at its exposed side is adapted to carry suitable advertising indicia.

15 In Figures 5 and 6 of the drawing there is shown a modification, wherein the ends 17 of the wire are received in a tubular coupling 18 and the plate 19 is worn by this coupling, the tongues 20 of the plate being bent about the 20 coupling for the fastening of the plate in place as will be clearly apparent in Figure 6 of the drawing.

The jaws or clips 10 and 11 are side by side and make contact with each other under inherent 25 resiliency thereof so that when the same are spread apart they have spring action toward each other for assuring a firm clamping of a part therebetween.

What is claimed is:

1. A device of the kind described, comprising a pair of coils arranged side by side and formed from a single length of inherently resilient wire, means at the ends of the wire for joining the same together and disposed to one side of one coil and toward the center thereof, and a display plate carried by said means.

2. A device of the kind described, comprising a pair of coils arranged side by side and formed from a single length of inherently resilient wire, means at the ends of the wire for joining the same together and disposed to one side of one coil and toward the center thereof, a display plate carried by said means, one of the coils having aligned bights transversely of the same, and an outbent portion formed from one of the coils to provide an entrance space between said coils.

3. A device of the kind described, comprising a pair of coils arranged side by side and formed from a single length of inherently resilient wire, means at the ends of the wire for joining the same together and disposed to one side of one coil and toward the center thereof, and a display plate carried at and overlying the joined ends of said wire.

GEORGE M. DOEBERT.
